UNITED STATES PATENT OFFICE

HERBERT H. DOW, OF MIDLAND, MICHIGAN, ASSIGNOR TO THE DOW CHEMICAL COMPANY, OF MIDLAND, MICHIGAN, A CORPORATION OF MICHIGAN

MEANS FOR VAPORIZING LIQUIDS

Application filed February 18, 1927. Serial No. 169,227.

Where liquids other than water are heated in boilers or vaporizers of usual type, as for instance in power plants operating with such a liquid e. g. volatilizable organic substances including oils and other hydrocarbons, and aromatic compounds such as diphenyl, diphenyl oxide, diphenylene oxide, etc., in substitution for water for vapor generation, I have found that there may be a tendency to decomposition and that this occurs in particular where vapor bubbles form on the hot metal and the surface burns dry. The prevention of such tendency with liquids of quite high boiling point, or liquids of lower boiling point and under high pressure, is accordingly highly desirable, making possible the continuous use of such liquids as a practical basis for the generation of vapor for power by expansion in a heat engine, or for heating or re-heating another power fluid in a power cycle, or still further for general use in indirect heating.

To the accomplishment of the foregoing and related ends, the invention, then, consists of the features hereinafter fully described, and particularly pointed out in the claims, the following description and the annexed drawing setting forth in detail but a few of the various ways in which the principle of the invention may be employed.

In said annexed drawing:—

Fig. 1 is a side elevational view and Fig. 2 is an end elevation of apparatus in accordance with the present invention; and Fig. 3 is an elevational detail.

The reference numeral 1 in the drawing designates a vapor-disengaging container having an outlet 2 to which an engine or other apparatus receiving or utilizing the disengaged vapors may be connected, the detail of such being immaterial to the present invention. In operative relation with the vapor disengaging container is a plurality of liquid-heating containers comprising a plurality of tubes 3, the lower ends of which end in lower drums 4a, 4b, and 4c and the upper ends of which end respectively in upper drums or headers 5a, 5b, and 5c. The tubes 3 it will be understood are arranged in a furnace so as to receive direct heat, but for the purpose of

illustration, and to avoid unnecessary complexity, the masonry of such a furnace chamber has been omitted from the drawing. The liquid-heating containers are maintained under pressure while in operation, but the vapor disengaging container 1 is free from such pressure. An active circulation or cycling of the liquid from the heaters to the vapor-disengager and back to the heaters and so on, is also provided for. Connections 6a, 6b, 6c extend between the headers or drums 5a, 5b and 5c and one end of the vapor-disengager 1, and from the other end of the vapor-disengager connections 7a, 7b, and 7c extend in turn to the lower drums 4a, 4b, and 4c. The pressure differential mentioned may be realized in some cases by a suitable constricting of the connections between the respective elements, but more conveniently I prefer to provide the pressure by arranging the vapor-disengager at a substantial elevation above the heaters, thereby attaining a hydraulic head to the extent predetermined for in particular conditions. A circulation of the liquid around through the respective elements results, it will be seen, from the thermosiphonic effect of the relation of heated and unheated elements, and if preferred, the circulation may be furthered and accentuated to any desired degree by setting in each or all of the pipes 7a, 7b, and 7c an impeller or pump, for instance a pump of rotary type as shown at 8, the pump casing constituting a portion of the connection 7 (7a, 7b, and 7c) and the shaft 9 of the rotor being driven by suitable means, as a motor 10.

The height at which the vapor-disengager will be positioned above the liquid-heater depends upon the amount of head and circulation required under conditions encountered. In general, doubling the vertical distance between the heater and vapor-disengager will double the differential pressure action, and also diminish by half the amount of circulation required to prevent bubble formation on the metal walls in the heater, and as will be readily understood, the particular requirements as to these will vary with the liquid being heated and vaporized, some of the organic liquids for instance of high molecular

weight and high boiling point requiring more pressure and circulation to prevent localized bubble formation than liquids having a lesser decomposable tendency.

5 Referring more specifically to the drawing, I contemplate in some cases arranging with a vapor-disengager 1 a set of multiple liquid-heating containers. These may be made up of banks of tubes 3 as in the foregoing, 10 each bank having upper and lower headers; in the illustration, (Figs. 1 and 2), 5a, 4a, and 5b, 4b, and 5c, 4c. That is, the upper headers 5a, 5b, 5c are in communication through respective connections 6a, 6b and 6c with the vapor-drum, and from the other end of the vapor-drum connections 7a, 7b and 7c communicate respectively with the drums 4a, 4b and 4c.

20 As will be seen from the foregoing, with the tubes 3 of the liquid-heaters subjected to furnace temperatures, and the contained liquid, for instance diphenyl oxide, pyrene, picene, etc., being under pressure and active movement from the circulation, vapor-bubble formation on the metal walls here is suppressed, and the liquid is swept on up to the vapor-disengager 1. Here, under the diminished pressure, vaporizing actively proceeds, to the extent engendered by the temperature 25 attained, and vapors are taken off at the outlet connection 2 to the further apparatus provided. The unvaporized liquid is in turn swept on down through the connections 7a, 7b, and 7c and again into the heater elements, to be again heated and forwarded to the vapor drum.

30 In this manner the requirements imposed by liquid of a decomposable character may be readily met, and without impracticable 40 complications of plant structure.

45 Other modes of applying the principle of the invention may be employed, change being made as regards the details disclosed, provided the steps or means stated in any of the following claims, or the equivalent of such, be employed.

I therefore particularly point out and distinctly claim as my invention:—

50 1. In an apparatus for generating vapor, the combination of a plurality of sets of top and bottom drums, a plurality of vertical liquid-heating tubes connecting the top and bottom drum in each set, each such set of top and bottom drums being located at slightly 55 overlapping progressively higher levels, and a vaporizing chamber in common connected with and elevated above said sets of drums, the connections between said chamber and said drums including ducts between one end of the chamber and the corresponding end of the top drums and ducts between the other end of the chamber and the corresponding end of the bottom drums.

60 2. In an apparatus for generating vapor, 65 the combination of a plurality of sets of simi-

larly inclined top and bottom drums, a plurality of vertical liquid-heating tubes connecting the top and bottom drum in each set, each such set of top and bottom drums being located at progressively higher levels, 70 a vaporizing chamber connected with and elevated above said sets of drums, the connections between said chamber and drums including ducts between one end of the chamber and the upper ends of the respective top drums and ducts between the other end of the chamber and the lower ends of the respective bottom drums, said vaporizing chamber being at a materially less pressure than the heating tubes and the drums.

Signed by me this 6th day of February, 1927.

HERBERT H. DOW.
